ATTORNEY

UNITED STATES PATENT OFFICE.

FRANK VICTOR POLAKOSKEY, OF PEEKSKILL, NEW YORK.

CLOTHES-PIN.

No. 884,680.

Specification of Letters Patent. Patented April 14, 1908.

Application filed March 21, 1906. Serial No. 307,162.

To all whom it may concern:

Be it known that I, FRANK VICTOR POLAKOSKEY, a citizen of Russia, and resident of Peekskill, in the county of Westchester and State of New York, have invented certain new and useful Improvements in Clothes-Pins, of which the following is a specification.

This invention relates to clothes pins, and to grips for suspending articles from lines generally.

It has for its objects, first, a means of utilizing an endless clothes line hanger that constitutes a separate application for a patent executed and filed by me March 21, 1906, Serial number 307163; second, a means of hanging articles to a clothes or other line that might soil the articles if hung over the line in the usual manner; and third, a useful device for hanging cards and merchandise on a line for display, as in stores.

The objects are attained by the means set forth in these specifications and the accompanying drawings, in which like letters refer to similar parts throughout the several views.

Figure 1 is a side view of the clothes pin. Fig. 2 is an edge view of the clothes pin. Fig. 3 is a view of the clothes pin open. Figs. 4 and 5 are views of two spring plates that form a part of the clothes pin. Fig. 6 is an edge view of and is a modification of one of the parts shown in Figs. 4 and 5. Fig. 7 is an enlarged section of Fig. 6. Fig. 8 is a front view of the part shown in Fig. 7. Fig. 9 is a fragmentary side view of a modification of the pin. Fig. 10 is a representation of the complete pin made of metal.

In the clothes pin shown the parts 1, 2, are of wood, and the spring 3 that holds them together is of steel and is stout. The pin thus formed is a commercial article and I make no claim upon it. It was selected because of its adaptability for the purpose and the plates *a*, *a*, are added to it. These plates are shaped as in Figs. 4, 5, 6. The angular parts 6 and 7 of the plates, shown edgewise in Fig. 6, have a slot 7' cut in one, and notches in the sides of the other, so that the plates interlock as in Figs. 1, 2, and 3. The parts 1, 2 of the clothes pin are held together by the spring 3, and holes 5, 5', Figs. 2, 4 and 5, are made in the plates through which the spring passes, so that when the spring is in place through the plates and the body parts of the clothes pin, the plates are held rigidly to the sides of the

clothes pin as in Figs. 1, 3. The angular parts 6, 7 have some elasticity so that they have the effect of springs when closing on a line, that is, the ends 9, 9 will close a little before the points *i*, *i* close.

The upper ends of the two plates have reverse curves 9, 9 so that when they come together as in Fig. 1, they will conform to the shape of a given size of clothes line. Fig. 3 shows the clothes pin in readiness to be closed on the line *l*. Articles to be hung up are grasped by the points of the pin *i*, *i*, and in hanging an article with this pin the pin is made to simultaneously close on both the article and the line. The parts 9 need not necessarily be the same size as the line for all purposes; but in hanging articles requiring two or more pins they should grasp the line to prevent the sagging of the article causing the pins to slide together. If the line be a little larger than the curved ends of the pin, the hold on the line by the pins would not be diminished.

In order to guard more effectually against the clothes pins slipping on the line, the parts 9 may be provided with one or more points, as 14, Figs. 6, 7 and 8. This point projects inwardly to engage with the line, and is shown to be made by means of punching it from the body of the metal.

In Fig. 9 the points *i*, *i* of the clothes pin are shown to have a provision for more firmly grasping an article, consisting of a notch 16 in one side of the pin, and a projection 15 on the other side to engage with the notch.

In Fig. 3 the action of the spring 3 in keeping the several parts together is illustrated. The point of the spring rests in a depression of the wood of the clothes pin, as at 12, and the plates *a*, *a* are held in place by the curvature of the spring outside of the plates. Instead of a hole in the plate a simple depression in the plate as at 5", Fig. 6, would not only answer the purpose, but would hold the plate more firmly. A slot 11, Fig. 3 gives room for the play of the spring. The plates *a* are applicable to any form of spring clothes pin, and when a different pin from that shown is used, it would be necessary to rivet the plates to the parts as shown at *c c c c*, Fig. 9.

As before stated, these gripping ends are shown as applied to this particular clothes pin because of its adaptability to the purpose; but their employment is not limited to this clothes pin. It is plain that the pin and

the spring gripping ends may be made integral, if made entirely of metal. For store use for hanging up articles for display and similar purposes, a small pin would preferably be made of metal, as shown in Fig. 10.

Having described my invention what I claim and desire to secure by Letters Patent, is—

1. In combination with a spring clothes pin spring plates attached to the sides thereof and extending above the pin, crossing each other and interlocking one with the other, and having curved terminals that close with the closing of the pin and open with the opening of the pin.
2. In combination with a clothes pin com-

prised of two parts held together by a circular spring, spring plates on the sides of the pin, the spring passing through holes in the plates to secure them in place on the pin, the plates extending above the pin, crossing each other and interlocking one with the other, and provided with curved terminals for closing over a line.

Signed at Peekskill in the county of West- 25
chester and State of New York this 16th day
of March A. D. 1906.

FRANK VICTOR POLAKOSKEY.
